(57) **CLAIM**

The ornamental design for a dispensing closure, as shown and described.

DESCRIPTION

FIG. 1 is a front isometric view of a first embodiment of a dispensing closure which is adapted for installation on a container (not shown), and FIG. 1 shows our new design of the dispensing closure in the closed condition as the dispensing closure would be initially configured for installation on a container (not shown) for initial purchase by a consumer;

FIG. 2 is a rear isometric view thereof;

FIG. 3 is a top plan view thereof;

FIG. 4 is a right side elevational view thereof, the left side elevational view thereof being a mirror image;

FIG. 5 is a front elevational view thereof;

FIG. 6 is a rear elevational view thereof;

FIG. 7 is a front isometric view of a second embodiment of a dispensing closure which is adapted for installation on a container (not shown), and FIG. 7 shows our new design of the second embodiment of the dispensing closure in the closed condition as the dispensing closure would be initially configured for installation on a container (not shown) for initial purchase by a consumer;

FIG. 8 is a rear isometric view of the second embodiment;

FIG. 9 is a top plan view of the second embodiment;

FIG. 10 is a right side elevational view of the second embodiment, the left side elevational view of the second embodiment being a mirror image;

FIG. 11 is a front elevational view of the second embodiment; and,

FIG. 12 is a rear elevational view of the second embodiment.

The broken line showing of a hinge in some of the figures depicts environment only and forms no part of the claimed design.
